CLAIM

The ornamental design for a shoe as shown and described.

DESCRIPTION

FIG. 1 is a side view of a shoe showing our new design; FIG. 2 is a front perspective view thereof; and, FIG. 3 is a rear perspective view thereof.

The broken line immediately adjacent to and surrounding the photographic area defines the peripheral bounds of the claimed design and forms no part thereof. The broken line showing of the region within the photographic area forms no part of the claimed design. The broken lines depicting the remainder of the shoe form no part of the claimed design.
